UNITED STATES PATENT OFFICE,

WILLIAM JANDUS, OF CLEVELAND, OHIO.

ELECTRIC-ARC LAMP.

SPECIFICATION forming part of Letters Patent No. 568,721, dated September 29, 1896.

Application filed March 5, 1896. Serial No. 581,989. (No model.)

To all whom it may concern:

Be it known that I, WILLIAM JANDUS, of Cleveland, in the county of Cuyahoga and State of Ohio, have invented certain new and useful Improvements in Electric-Arc Lamps; and I do hereby declare the following to be a full, clear, and exact description of the invention, such as will enable others skilled in the art to which it appertains to make and use the same.

My invention relates to an improvement in electric-arc lamps, and more particularly to improvements on the arc-lamp for which Letters Patent were granted to me July 23, 1895, No. 543,445, the object of the present invention being to improve and simplify the construction, in various respects, of the lamp disclosed by said patent, so as to better adapt the leading features embodied to lamps of smaller type.

With this object in view the invention consists in certain novel features of construction and combinations and arrangements of parts, as hereinafter set forth, and pointed out in the claims.

In the accompanying drawings, Figure 1 is a sectional view of my improved lamp. Figs. 2, 3, 4, 5, 6, 7, and 8 are detail views.

A represents a casing, preferably of sheet metal, having an opening in its cap A'. A casting 1 is disposed within the cap A' and provided with a screw-threaded shank 2, which projects through an opening in the top of the cap. On this shank a head or knob 3 is screwed and adapted to bear on top the cap A', and said head or knob is made with openings 4 for the accommodation of the leading-in wires. The lower portion of the casting 1 is made with an annular internally-screw-threaded flange 6 for the reception of an externally-screw-threaded sleeve 7, the latter having an inwardly-projecting annular flange 8, which serves to retain in place an internally-screw-threaded collar 9, insulating-washers 10 being disposed between said collar and the casting 1 and annular flange 8 of sleeve 7, respectively. The collar 9 sustains a tube 11, the upper end of which is screwed thereto. The tube 11 extends downwardly from its support in the cap A', passes through the upper portion of the core 12 of the separating and feeding magnet, and terminates in

the upper end of the hollow or tubular armature 13 of said magnet, for which it serves as a guide. The core 12 of the magnet is made with a recess or concavity 14 in the form of a truncated cone for the reception of the similarly-shaped upper end of the armature 13, and said core is supported by a collar 15, integral with the upper end of a cylindrical frame or shell 16, of iron. A sleeve 17, preferably of brass or other non-magnetic metal and of an external diameter equal to that of the core 12, is secured at its upper end to the lower end of said core and extends downwardly to a point in proximity to the lower end of the frame or shell 16, where it terminates in a laterally-projecting annular flange 18, the periphery of which is disposed under a shoulder 19 near the lower end of said shell. The sleeve 17 forms, with the core 12 and frame or shell 16, an annular compartment 19 for the reception of the coil 20 of the magnet, the annular flange 18 on the sleeve 17 serving as a bottom support for said coil. The armature 13 moves freely and without cushion or contact within the sleeve 17.

From the shoulder 19 an annular flange 21 depends from the magnet frame or shell 16 for the reception of the upper end of a cylinder 22, which is tightly fitted to said flange, so as to have good magnetic contact therewith, and forms in effect an extension of said frame or shell. A tubular neck 23 projects downwardly from and communicates with the cylinder 22 and terminates at its lower end in an inverted-dish-shaped portion 24, which forms the upper portion of the brush-holder, as more fully explained farther on, the portion 25 of said neck being made as small as possible, so that the amount of heat conducted by it will be reduced to a minimum, and the said portion 25 of the neck is braced by means of ribs 25.

Within the cylinder 22 an iron cup or pan 26 is disposed and secured to the lower end of the armature 13, said cup or pan forming, in effect, a piston. The cup or pan 26, which constitutes part of the armature 13, has a close but sliding contact with a brass lining 27 in the cylinder 22, said lining serving to prevent actual magnetic contact with the wall of the cylinder, which contact, if per-

mitted, would tend to interfere with the proper operation of the cylinder. From this construction and arrangement of parts it will be seen that an air-cushion for the armature 5 will be formed below the cup or pan. The upper end of the lining 27 may be made with a flange 30, inserted between the upper end of the cylinder 22 and the annular flange 18 on the sleeve 17. The said lining is extended 10 over the bottom of the cylinder 22 and made with a bulge, as at 31, and then downwardly, so as to form a lining 32 in the neck 23. The cup or pan 26 is made with a tubular extension 33, which enters the neck 23 and has 15 close but sliding contact with the lining 32, and thus assists in the maintenance of the air-cushion under the cup or pan while the latter moves up and down. A tube 34, the upper end of which terminates within the 20 lower end of the tubular armature 13, serves to effect the operation of clutch release in a manner presently explained. The clutch-pan 26 is made with an inclined or sloping wall 35, which is knurled or roughened, and 25 within this pan the clutch is disposed. The clutch is composed of a series of rings 36, each preferably having a V-shaped peripheral groove 36^a, and the periphery of each clutch-ring is knurled or roughened. The 30 clutch-rings project through elongated slots 37 in the tubular core 13 and engage the upper carbon, passing through the latter, said clutch-rings being retained in their relative slots 37 by means of a ring 38, which passes 35 through said clutch-rings, preventing them from falling inward far enough to cause them to wedge when carbon is inserted. From this construction and arrangement of parts it will be seen that when the armature 13 40 moves upwardly the clutch-rings will grasp the upper carbon and raise the same, and that when the armature moves downwardly said clutch-rings will, by their engagement with the upper end of the tube 34, be so moved laterally as to release the carbon and 45 permit it to feed. The upper carbon C' is carried by a holder C, comprising an insulating-piece j, preferably of hard porcelain, with a tube extension k and carbon socket or 50 clamp l. The carbon rod fits this socket on a shoulder, the carbon forming a continuous and unbroken surface with the socket-piece. The porcelain insulator is so arranged as to 55 position on the holder that when the carbon is consumed to a predetermined point the insulator just enters the brush-rings 36 and cuts off the current from the carbon and opens-circuits the lamp.

The inverted-dish-shaped casting 24 at the 60 lower end of the neck 23, as before stated, forms the upper part of the brush holder or box 38, the lower portion 39 of said holder or box being formed by a collar 40 at the upper end of the arms 41, which support the lower-carbon holder, said collar being made at its 65 lower end with an annular flange or shoulder 42, on which a disk 43, of porcelain or other

insulating material, rests, which disk constitutes the bottom of the brush holder or box and is made with a central opening 44 for the 70 passage of the upper carbon. The brush 45 (with which the positive terminal of the lamp is connected through the magnet-frame) is composed of a series of rings sustained by a support 46, so as to have a yielding contact 75 with the upper carbon. The porcelain bottom of the brush-box will prevent short-circuiting, which might occur in the lamp if the brush-rings or the electrode should come in contact with a metallic bottom in the brush-box. The upper end of the collar 40 bears against an annular plate 47, having a peripheral flange or extension 48, and between said plate and the casting 24 a ring 49, of insulating material, is disposed. The brush and the 80 parts with which it is electrically connected are thus electrically separated from the arms 41, which support the lower-carbon holder.

A ring 50, of insulating material, is placed on the extension 48 of plate 47 and rests at 90 its inner edge on the insulating-ring 49. Between the ring 50 and an annular flange 51 on the casting 24 a plate or ring 52 is preferably disposed. To the flange 51 of casting 24 an annular box or receptacle 54 is secured 95 by means of arms 55, but from which flange said box or receptacle 54 is insulated, the casing of the lamp being made with an extension 55 for the accommodation of the latter. A coil 56, of resistance material, is placed 100 within the annular box or receptacle and enclosed by means of a cover 57.

Binding-posts a b c d e f are provided for the resistance-coil, the binding-post a being connected with one end of said coil, the post 105 f connected with the other end, and the posts b c d e connected with said coil at intermediate points, so that the connections can be adjusted to include more or less resistance in the circuit, according to the strength of current on the circuit where the lamp is to be used. The binding-post a is electrically connected with a screw g, which latter is electrically connected with the collar 40 at the 110 upper end of arms 41. The binding-post f 115 (or one of the intermediate binding-posts) is connected directly with the negative terminal of the lamp by a wire h.

The arms 41, which constitute a frame for supporting the lower-carbon holder and both 120 globes, are made at their lower ends with a ring 57, having a series of notches 58 to permit the passage of lugs 58^a at the free ends of a series of arms 59. The arms 59 radiate from a socket-piece 60, which constitutes a 125 holder for the inner globe 64, the neck of which is secured in said holder by means of a screw 64^a. When the lugs at the free ends of the arms 59 shall have been passed through the notches 58 in ring 57, the globe-holder 130 will be given a quarter-turn or until one of the arms engages a stop 59^a on the ring, when said lugs 58^a will rest on said ring and the globe-holder 60 be supported by the latter,

accidental displacement of the globe-holder being prevented by a set-screw 60^a.

The globe 64 is provided with a double cover 65, having perforations 66 66^a for the passage of the upper carbon, which latter is of considerably less diameter than said perforations. The parts of the cover are so disposed as to form a chamber 67 between them, and in this chamber a disk-valve 68 is loosely disposed and made with a hole 69, through which the upper carbon neatly passes.

The socket piece or holder 60 is made in its center with a sleeve 70, a portion of which projects upwardly within the socket, and a portion extends downwardly below the same, the downwardly-extending portion being provided at its lower end with screw-threads 70^b, and said sleeve serves as a holder for the lower carbon, the latter being held in place by means of a screw 70^b. The lower screw-threaded end of the sleeve or holder 70 enters a nut 71 and said nut is made with a tubular, internally-screw-threaded shank 72, the lower portion of which passes freely through a hole in a porcelain knob 73, the latter being retained in position by the head of the knob 73 bearing against the lower end of a collar 75, made at the center of a plate or clamp 76, the latter resting against the under face of the outer globe 77 and forming a portion of the holder for the same. Another clamp or plate 76^a (forming the other portion of the holder for the outer globe) engages the inner face of the outer globe and its inner portion is curved and made to conform to the nut 71 and has an annular flange 78 disposed under the nut, an insulating washer 79 being disposed between said flange and the plate or clamp 76. The upper edge of the outer globe 77 bears against the plate 48 (or the insulating-ring 50) and is retained in close contact therewith, so as to make the globe 77 air-tight at its upper end, by means of the connections above described between said globe and the arms 41. The plates 76 76^a are made with perforations 76^b 76^c, respectively, which perforations are normally closed by a valve 80. The valve 80 is made with a depending annular flange 81, which is guided on the upper portion of the porcelain knob 73, and within said annular flange a spring 82 is disposed, said spring bearing at its respective ends against the knob and valve and serving to normally retain the latter closed.

When it is desired to supply the lamp with carbons, the outer globe 77 will first be removed by loosening or unscrewing the nut 71 from carbon-holder 70. The lower-carbon holder and inner globe will then be removed by making a quarter-turn, so as to release the arms 59 of holder 60 from the arms' ring 57, the set-screw 60^a having first been unscrewed. It is necessary to employ the set-screw 60^a, not only to prevent accidental displacement of the parts, as above mentioned, but also to permit the globe-sup-

porting nut to be unscrewed from the lower holder without causing said holder to fall out. It will also be observed that the armature 13 70 closes the magnetic circuit through itself and the pole-piece and the lower portion of the magnet-frame. The magnetic circuit of the magnet is permanently closed through the armature by having the latter completely 75 closed within the magnet-body, so that the armature is at all times within the magnetic field and may be actuated by the slightest change in the magnetic force of the magnet caused by electric fluctuations in the coil. 80

By making the upper end of the armature tapering and providing a similarly-shaped recess or concavity in the pole-piece a uniform pull through the whole movement of the armature will be effected. 85

The circuit through the lamp is as follows: The plus leading-in wire *i* enters lamp through the hole 4 in the knob 3 and then passes downwardly and is connected to one end of the coil of the magnet, the other end of 90 said coil being connected to the frame of the magnet. The current then passes through the magnet frame or casing and is delivered to the upper carbon by the clutch and the brush 45. The current then passes from the 95 upper to the lower carbon and then from the lower-carbon holder to the arms 41. From the arms 41 and collar 40 the current passes through the screw *g* to one terminal of the resistance and from the other terminal of the 100 resistance the current flows to the negative terminal of the lamp.

When the circuit through the lamp is closed, the magnet will be energized and its armature caused to move upward, resulting 105 in a separation of the carbons to form the arc. As the piston-like cup or pan 26 and its depending tubular extension 33 move upwardly the first pull of the armature will be against a partial vacuum, whereby the first upward 110 movement of the carbon in striking the arc will be even and without jerk.

When the armature-pan 26 has been raised, sufficient air will have entered below to form a cushion for the same, so that the armature 115 will now be perfectly cushioned in its movement in either direction. This cushion will dispense with the necessity of the armature having air-cushion in the magnet-bore, so that the fit of the armature in said bore will 120 not require to be very snug, whereby binding of the armature in the bore is prevented. The pan 26 being of a proper proportionately large diameter will not require a very snug fit in the casing at the bottom of the magnet, 125 for which reason another source of binding of the armature is prevented. The knurling or other roughening of the clutch-rings and the flaring interior of the armature-pan will cause said rings to clutch the carbon or carbon-sheath with a grip which is positive and will not admit of the carbon slipping down while the armature is raised. As the armature-pan 26 is of the same material as the

- cylindrical casing within which it has air-cushioned play, said pan will not bind in the casing on account of expanding by the heat ascending from the arc, as the expansion of the cylindrical casing equals the expansion of the pan, and the brass lining of the casing will, on account of the greater coefficient of expansion of brass than of iron, expand with the casing and offer no resistance to the expansion of the same. The lower portion of the magnet structure air-tightly surrounds the tubular armature and clutch mechanism, so that the ornamental and protective casing which surrounds the upper portion of the lamp structure will not require to be air-tight at any point, but may be ventilated at any suitable or desired point wherever ventilation may be required to keep the operative portions of the lamp cool. The arrangement of the annular rheostat at a point above the arc inclosure and below the feed mechanism and surrounding the lamp structure, with an air-space between it and said structure, will keep the rheostat from being heated from the arc and place it at a point where it will not occupy room required for the regulating mechanism and where it will adapt itself to the ornamental outline of the lamp.

My improvements are simple in construction and effectual in all respects in the performance of their functions.

Some slight changes might be made in the details of construction of my invention without departing from the spirit thereof or limiting its scope, and hence I do not wish to limit myself in the precise details of construction herein set forth; but,

Having fully described my invention, what I claim as new, and desire to secure by Letters Patent, is—

1. In an arc-lamp, the combination with a shell, of a pole-piece depending into the upper portion of said shell, the lower end of the shell forming a cylinder, a coil encircling said pole-piece, an armature adapted to enter said coil and terminate at its lower end in said cylinder, and a piston secured to the lower end of said armature and operating in said cylinder, substantially as set forth.
2. In an arc-lamp, the combination with a magnet and its armature, of a cylinder encircling the armature, an extension depending from said cylinder, a piston secured to the armature and operating in said cylinder so as to form air-cushions in the lower parts of said cylinder and an extension on said piston adapted to operate in the extension of the cylinder, substantially as set forth.
3. In an arc-lamp, the combination with a magnet and its armature, the latter having slots therein, of a clutch-pan secured to the lower end of the armature, a cylinder in which said clutch-pan neatly fits and moves, clutch-rings in the clutch-pan and projecting through the slots in the armature so as to engage the carbon therein, and a fixed device adapted to project into the opening in said armature

and release the clutch-rings from the carbon, substantially as set forth.

4. In an arc-lamp, the combination with a magnet and its armature, of a cylinder encircling the armature and having a tubular extension or neck, a lining in said cylinder, a lining in the tubular extension or neck, a cup or enlargement secured to the armature and operating in said cylinder and an extension on said cup or enlargement and operating in said tubular extension or neck in contact with the lining in the latter, substantially as set forth.

5. In an arc-lamp, the combination with a magnet and its armature adapted to receive the upper carbon of the lamp, of a cup or pan secured to the armature, clutch-rings in said cup or pan and projecting through slots in the armature so as to engage the carbon, a tubular extension depending from said cup and communicating with the opening therein and with the opening in the armature, and a sleeve projecting up through said tubular extension and adapted to enter the lower end of the armature and release the clutch-rings from the carbon, substantially as set forth.

6. In an arc-lamp, the combination with a magnet and its core, of a cup or pan secured to the armature and having a tubular extension depending therefrom, a cylinder in which said cup or pan operates, clutch-rings in the cup and adapted to project through slots in the armature to engage the carbon in the latter, a lining in the cylinder, a neck on the cylinder, a lining in said neck, said linings being made in a single piece, and a sleeve projecting up through the tubular extension on the cup and adapted to enter the lower end of the armature, substantially as set forth.

7. In an arc-lamp, the combination with a magnet and its armature and a cup or enlargement secured to said armature, of a cylinder encircling the armature and in which said cup or enlargement operates, and a neck depending from said cylinder and communicating therewith, said neck being made small and having strengthening-ribs, substantially as set forth.

8. In an arc-lamp, the combination with a magnet and its armature, of a cylinder in which the lower portion of the armature operates, a neck depending from said cylinder, an inverted-dish-shaped portion at the lower end of said neck and forming part of a brush-holder, arms for supporting the lower-carbon holder, a collar at the upper ends of said arms forming the lower portion of said holder and insulated from said dish-shaped upper portion and a brush in said brush-holder and electrically connected with the upper portion thereof, substantially as set forth.

9. In an arc-lamp, the combination with the magnet and its armature, of a cylinder encircling the lower portion of the armature, a neck on said cylinder formed at its lower end to constitute a part of a brush-holder, arms for supporting the lower-carbon holder,

a collar at the upper end of said arms forming the lower portion of the brush-holder and insulated from the upper portion thereof, a flange or shoulder in said collar, a non-metallic bottom for the brush-holder on said flange or shoulder, and a brush in said holder, substantially as set forth.

5 10. In an arc-lamp, the combination with a sheet-metal casing having a laterally-projecting annular enlargement at its lower end, of a rigid framework within said casing, an annular box secured to said framework and projecting laterally into said annular enlargement at the lower end of the casing and a resistance in said box, substantially as set forth.

15 11. An arc-lamp comprising a body and clutch mechanism and an annular rheostat surrounding said body below the clutch mechanism, substantially as set forth.

20 12. In an arc-lamp, the combination with a casing having an annular enlargement at its lower end, a magnet in the casing, a casting supported by the magnet, arms for supporting the lower-carbon holder, said arms being secured to said casting and insulated therefrom, an annular box or compartment within the enlargement of the casing and secured to said casting, a resistance-coil in said box or compartment, one end of said resistance-coil being electrically connected with the arms which support the lower-carbon holder and the other end of said coil being connected with the negative terminal of the lamp, substantially as set forth.

25 13. In an arc-lamp, the combination with a casing having an enlargement at its lower end, of a casting supported within the casing, an annular box disposed within the enlarged portion of the casing, and arms secured at their respective ends to the casting and annular box, substantially as set forth.

30 14. In an arc-lamp, the combination with the casing, of arms depending below the casing, a socket-piece removably connected to said arms and constituting a support for an inner arc-inclosing globe, a sleeve in the center of said socket-piece and constituting a lower-carbon holder, a nut on said sleeve and means for securing an outer globe to said nut, substantially as set forth.

35 15. In an arc-lamp, the combination with the casing and arms depending below the same, of a notched ring at the lower ends of said arms, a socket-piece for the reception of an inner arc-inclosing globe, arms projecting from said socket-piece and removably supported by said ring, a stop to limit the movement of said arms when they are attached to said ring, a set-screw for preventing the arms

40 45 and socket-piece from displacement, a lower-carbon holder carried by said socket-piece, a nut on said lower-carbon holder, and means for attaching an outer globe to said nut, substantially as set forth.

50 55 60 65 16. In an arc-lamp, the combination with a casing and arms depending therefrom, of a socket-piece removably attached to said arms

and adapted for the reception of the neck of an inner arc-inclosing globe, a sleeve in said socket-piece constituting a lower-carbon holder, a nut on the lower end of said sleeve, means for securing an outer globe to said nut, and an insulated ring above said arms, against which said globe bears and with which it has an air-tight fit, substantially as set forth.

70 17. In an arc-lamp, the combination with a lower-carbon holder having a depending screw-threaded extension, of a nut on said extension, a depending shank on said nut, a globe having a sealed top, a knob secured on said shank, and a valved globe-holder between said nut and knob, substantially as set forth.

75 18. In an arc-lamp, the combination with a lower-carbon holder having a depending externally-screw-threaded extension, of a nut on said extension, said nut having a depending internally-screw-threaded shank, a globe, a knob on said shank, a screw entering the shank and holding the knob in place, and a globe-holder between the knob and nut, substantially as set forth.

brush of the lamp and cut off the current from the electrode and the latter retained in a vertical position by the upper section of said electrode-holder, substantially as set forth.

5 23. In an arc-lamp, the combination with the main frame carrying the separating and feeding mechanism of the lamp, and forming part of the lamp-circuit, a depending frame secured to and insulated from the main frame 10 and a lower-carbon holder carried by said depending frame, of a brush-holder formed by the meeting portions of the two frames, and a perforated bottom in said brush-holder, said perforated bottom being of non-metallic material, whereby to prevent short-circuiting of the lower carbon, substantially as set forth.

24. In an electric lamp, the combination with a hollow magnet structure having a cylindrical chamber and an annular chamber 20 communicating with the cylindrical chamber, of an armature having the feed-clutch mechanism supported within it and formed with a cylindrical portion which has play and air-cushion in the cylindrical chamber and with 25 a tubular portion which has play and air-cushion in the annular chamber, substantially as set forth.

25. In an electric lamp, the combination with a hollow magnet structure having an axial chamber, a cylindrical chamber communicating with said chamber, and an annular chamber communicating with the cylindrical chamber, of an armature having the feed-clutch mechanism supported within it and 30 formed with a portion axially movable in the axial chamber, with a cylindrical portion having axial play and air-cushion in the cylindrical chamber, and with a tubular portion having axial play and air-cushion in the annular chamber, substantially as set forth.

35 26. In an electric lamp, the combination of an arc inclosure air-tight at its upper end, a hollow and air-tight magnet structure having communication at its lower end with the upper end of said arc inclosure and formed with 40

an axial chamber and a cylindrical chamber communicating therewith, and an armature having the feed-clutch mechanism supported within it and having an axial portion axially movable in the axial chamber and a cylindrical portion having axial movement and air-cushion in the cylindrical chamber, substantially 50 as set forth.

27. In an electric lamp, the combination with an arc inclosure air-tight at its upper 55 end, a hollow and air-tight magnet structure having communication at its lower end with the upper end of said arc inclosure and formed with an axial chamber and a cylindrical chamber communicating therewith and with an annular chamber communicating with the cylindrical chamber, an armature having the feed-clutch mechanism supported within it and having an axial portion axially movable in the axial chamber and a cylindrical portion 60 and a tubular portion having axial play and air-cushion respectively in the cylindrical and annular chamber, substantially as set forth.

28. In an electric lamp, the combination with the upper lamp structure formed with an annular flange at its lower end, a metal washer against the under side of said flange, an asbestos washer against the under side of said metal washer, a metallic washer against the 75 underside of the asbestos washer and clamped to have its outer edge spring downward from said latter washer, and a lower-carbon frame, of a globe having its upper edge seated against said spring-washer, and means for forcing 80 said globe against the washers and flange, substantially as set forth.

In testimony whereof I have signed this specification in the presence of two subscribing witnesses.

WILLIAM JANDUS.
